US00D924504S

(12) **United States Design Patent** (10) **Patent No.:** **US D924,504 S**
(45) **Date of Patent:** **** Jul. 6, 2021**

(54) **VACUUM CLEANER**

(71) Applicant: **BISSELL Inc.**, Grand Rapids, MI (US)

(72) Inventors: **Mackenzie L. Knapp**, Saranac, MI (US); **Derek E. Smith**, Grand Rapids, MI (US)

(73) Assignee: **BISSELL Inc.**, Grand Rapids, MI (US)

(**) Term: **15 Years**

(21) Appl. No.: **29/683,977**

(22) Filed: **Mar. 18, 2019**

(51) LOC (13) Cl. **15-05**

(52) U.S. Cl.

USPC **D32/21**

(57) **CLAIM**

The ornamental design for a vacuum cleaner, as shown and described.

DESCRIPTION

FIG. 1 is a front perspective view of a vacuum cleaner showing our new design;

FIG. 2 is a front view thereof;

FIG. 3 is a left side view thereof;

FIG. 4 is a right side view thereof;

FIG. 5 is an enlarged top view of the vacuum cleaner;

FIG. 6 is an enlarged front perspective view of a lower portion of the vacuum cleaner shown in FIG. 1; and,

FIG. 7 is an enlarged front view of a lower portion of the vacuum cleaner shown in FIG. 2.

The details of the vacuum cleaner shown in broken lines form no part of the claimed design.

1 Claim, 7 Drawing Sheets
